UNITED STATES PATENT OFFICE

LEWIS WHITE, OF PAWTUCKET, RHODE ISLAND, ASSIGNOR TO HUSSONG DYEING MACHINE COMPANY, OF GROVEVILLE, NEW JERSEY, A CORPORATION OF NEW JERSEY

DYEING APPARATUS

Application filed August 17, 1928. Serial No. 300,326.

In dyeing skeins of material it has been the custom to suspend the skeins on rods supported in the dyeing solution, and to cause upward currents through the solution to slightly displace the skeins on the rods, in order to satisfactorily dye that portion resting thereon.

A serious difficulty encountered in such procedure is that substantially horizontal cross currents occur, which counteract the lifting action, resulting in streaked portions in the skeins. Attempts to avoid this have been made, using increased pressure to establish the desired currents. Such methods were largely unsuccessful, inasmuch as the currents of liquid so produced impinged violently on the walls of the container, resulting in agitation of the liquid and consequent streaking of the treated material. Thus streaking of one form or another has been difficult to avoid.

By my invention the above difficulties have been avoided by arranging a readily accessible overflow of large area for the upwardly using liquid. In this manner the tendency to produce eddy currents is avoided.

An object of my invention is to arrange means by which to avoid the above enumerated difficulties.

Another object is to arrange an overflow of large volume for the dyeing of a dyeing apparatus.

Another object is to construct a new and improved type of baffle for the liquor of a dyeing machine.

A still further object is to provide an overflow gutter or channel for a dyeing machine, combined with a new type of baffle to properly guide the flow of liquor to and from the gutter.

Other objects will present themselves in the light of the description and appended claims.

In the accompanying drawing:

Fig. 1 is a plan view of a dye vat made in accordance with my invention;

Fig. 2 is a longitudinal sectional view on the line 2—2, Fig. 1;

Fig. 3 is a transverse sectional view on the line 3—3, Fig. 1; and

Fig. 4 is a transverse sectional view on the line 4—4, Fig. 1.

The dyeing machine comprises a base member 1 on which is mounted side walls 2, 3, and end walls 4 and 5. Adjacent the side walls 2 and 3 and the end wall 5 is a trough or gutter 6, which as seen in Fig. 2 extends diagonally upward from left to right.

As will be seen from Figs. 1, 2 and 4, the dyeing chamber is closed by a false bottom 1^a having a plurality of perforations or slots 1^b therein. Liquid channels 1^c from the propelling chamber to the dyeing chamber are defined by spacing members 1^d which are supported by suitable means such as channel members 1^e, shown in Figs. 2 and 4. By these means the dyeing liquid can be forced in a uniform manner through all portions of the dyeing chamber.

The gutter or channel 6 may be formed in any suitable manner, one form of which as shown comprises laterally extending portions 7 secured to the adjacent walls by any desired means with wings 8 extending upwardly from 7. These wings extend beyond the edges of walls 2, 3 and 5.

A cover member 9 extends across the top of wall 4, and terminates at its inner end in a downwardly extending baffle 10. While the cover 9 extends across the full width of the apparatus, the baffle 10 extends only across the dyeing chamber, designated at 11, and defined by base 1, walls 2, 3, 5 and baffle 10.

Slightly inset from wall 5 is another baffle 12, similar to 10. The purpose of these baffles will be developed later.

Suitable agitating means may be employed. As shown, one or more horizontally extending propellers 13 may be secured to vertical shafts 14 journaled in openings 15 in cover 9. These propellers may operate within closely surrounding cylindrical jackets 16 which are conveniently supported as by closure member 17.

Although these propellers may be arranged horizontally if desired, it is preferred to arrange them to force the liquid to traverse a substantially vertical path.

The material to be dyed is suspended in

the central portion 11, any suitable frame for carrying the material being employed. The propellers are put into operation, the shafts being operated from any suitable power source (not shown) and the liquor is forced down underneath baffle 10, past curved portion 18 in the direction of the arrows of Fig. 2, and thence upwardly where it overflows the edges into the trough or gutter 6.

13 Instead of hitting the wall 5 and rebounding to establish the undesirable eddy currents, the liquor will travel upwardly through the passage between wall 5 and baffle 12 with but little resistance being offered, and lifting 15 the check valve 19, will flow into gutter 6. In this manner an overflow outlet of large area and volume is provided. The overflow will descend the trough 6 by gravity, and will again pass through the propeller housing. 20 The liquors traveling upwardly will lift the skeins and dye the material uniformly. The motion of the liquid is continuous and is not sufficiently rapid to agitate it.

Upon reversal of the propeller action the 25 dye will be forced back up the trough to overflow throughout its length into chamber 11. At this time the check valve 19 will remain seated, due to the pressure of the liquid, and the dye will be efficiently directed into chamber 11.

As will be readily seen, this invention is susceptible to numerous modifications, and it is intended that it be limited only by the scope of the appended claims.

25 I claim:

1. In a dyeing apparatus, a dyeing chamber, means for circulating a dyeing liquid through said chamber, and a gutter around the outside of the chamber, extending diagonally down the sides of the container, for receiving the overflow from the chamber and returning it to the circulating means.

2. In a dyeing apparatus, a dyeing chamber, a dyeing liquid therein, a propeller arranged on a vertical shaft, for circulating the dyeing liquid through the chamber, and a gutter around the outside of the chamber and slanting downwardly in the direction of the propeller, to receive the overflow from the chamber and return it to the propeller, and means connecting the gutter with the region adjacent the propeller.

3. In a dyeing apparatus, a dyeing chamber, propelling means arranged at one end thereof to circulate the dyeing liquid through the chamber, and a gutter extending around the sides and the opposite end of the chamber, slanting diagonally down towards and communicating with the propelling means to receive the overflow from the chamber and to discharge it into said propelling means.

4. In a dyeing apparatus, a dyeing chamber, means at one end thereof for circulating a dyeing liquid through the chamber, and 65 a baffle extending short of the bottom of the

chamber at the opposite end thereof, defining a passageway for the liquid between the baffle and the adjacent wall of the container, and a check valve at the upper end of the passageway, permitting overflow, but closing the 70 passageway against movement in the opposite direction.

5. A dyeing apparatus comprising a dyeing chamber and a liquid-agitating chamber, a baffle downwardly extending nearly to the bottom of the dyeing chamber adjacent the wall opposite to the agitating chamber, the baffle thus defining a passageway, and a valve at the upper end of the passageway to permit flow in an upward direction, but to close the 75 passageway against a downward flow.

6. A dyeing apparatus comprising a dyeing chamber and a propeller chamber, a barrier extending downwardly short of the bottom of the dyeing chamber adjacent the wall opposite to the propeller chamber, the barrier thus defining a passageway, and a check valve at the upper end of the passageway.

7. A dyeing apparatus comprising a dyeing chamber and a liquid agitating chamber; a gutter extending around the exterior of the dyeing chamber and slanting downwardly towards the agitating chamber, to accommodate overflow from the dyeing chamber and return it to the agitating chamber, a baffle extending nearly to the bottom of the dyeing chamber adjacent the wall opposite the agitating chamber, the baffle thus defining a passageway of little resistance, to prevent 90 eddy currents in the liquid, and a check valve 95 at the upper end of the passageway.

8. In a dyeing apparatus, a dyeing chamber, a propeller chamber at one side thereof and communicating therewith, a propeller in said propeller chamber with its blades revolvable through a horizontal plane, and about a vertical axis, a gutter around the outer side of the other sides of the dyeing chamber, to accommodate the overflow from the chamber, and slanting downwardly towards the propeller chamber to return the overflow thereto, and a baffle extending short of the bottom of the dyeing chamber adjacent the wall opposite the propeller chamber, thus defining a passageway, and a check valve closing the 105 110 115 passageway.

9. In a dyeing apparatus, a dyeing chamber, a propeller chamber at one side thereof and communicating therewith, a propeller in said propeller chamber with its blades revolvable through a horizontal plane, and about a vertical axis, a gutter around the outer side of the other sides of the dyeing chamber, to accommodate the overflow from the chamber, and slanting downwardly towards the propeller chamber to return the overflow thereto, and a baffle extending short of the bottom of the dyeing chamber adjacent the wall opposite the propeller chamber, thus defining a 120 125 130 passageway, a check valve closing the pas-

sageway, said dyeing chamber having a perforated false bottom, and graduated barriers between said propeller chamber and the dyeing chamber, to uniformly distribute the dyeing liquid from the propeller chamber through the false bottom of the dyeing chamber.
